Primary Examiner — Lucy Lieberman

(57) **CLAIM**

The ornamental design for a watch, as shown and described.

DESCRIPTION

FIG. 1 is a front elevation of a watch showing our new design;

FIG. 2 is a right side elevation thereof;

FIG. 3 is a left side elevation thereof;

FIG. 4 is a rear elevation thereof;

FIG. 5 is a front and right side perspective view thereof; and,

FIG. 6 is an end view thereof.

The broken lines in the drawings are for illustrative purposes only and do not form part of the claimed design.
